UNITED STATES PATENT OFFICE.

HENRY C. DES COMBES, OF CHILHOWEE, MISSOURI.

SEAL.

1,334,353.

Specification of Letters Patent. Patented Mar. 23, 1920.

Application filed September 6, 1919. Serial No. 322,115.

To all whom it may concern:

Be it known that I, HENRY C. DES COMBES, a citizen of the United States, residing at Chilhowee, in the county of Johnson and State of Missouri, have invented a new and useful Seal, of which the following is a specification.

This invention relates to improvements in seals, and more particularly to seals employed for locking milk can covers, or the like.

The primary object of the invention is to provide a seal having an adjustable shackle, thereby adapting the seal for use with various sized cans.

A further object of the invention is to provide a device of this character having locking tongues, stamped from the sheet of metal of which the seal is formed, and means for providing a guard for the tongues, to prevent bending of the tongues out of locking engagement with the shackle, in the event that the seal is being tampered with.

A still further object of the invention is to provide a seal wherein all of the elements thereof, are stamped from a single sheet of metal, the locking elements being constructed to automatically lock the shackle to the body, against displacement when the shackle is moved to its locked position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

Referring to the drawing:-

Figure 1 illustrates a seal constructed in accordance with the present invention, the same being shown in its locked condition.

Fig. 2 illustrates a sectional view taken on line 2-2 of Fig. 1.

Fig. 3 illustrates a blank constructed in accordance with the present invention, the same being shown in a partially folded condition.

Referring to the drawing in detail, the reference character 5 designates the central portion of the body or housing of the seal, the same being shown as provided with an extension 6, which is relatively long, and

provided with circular openings 7, disposed throughout substantially, its entire length in spaced relation with each other, the extreme end of the extension, or shackle 6, being reduced as at 8, for purposes to be hereinafter more fully described.

The central portion 5, of the body is provided with depressed portions 9 and 10, the same being in spaced relation with each other, and in a position to house the extreme ends of the locking tongues 11 and 12, formed in lateral section 13, of the body, when the section is folded to overlie the central portion 5, of the body.

As shown, the lateral section 13, is provided with a shoulder 14, spaced from one edge of the shackle 6, to insure the section 13, being bent or formed in proper relation with the central section 5, so that the locking tongues 11 and 12, will assume a proper relation with the depressions 9 and 10.

A lateral section 15, is disposed adjacent the opposite side of the central portion 5, the same being provided with relatively narrow section 15, formed integral therewith, the same being folded on the line 17, the distance between the line 17, and the line 18, on which the section 15 is folded, being substantially the same as the width of the central section 5 of the body, so that the sections 13, 15 and 5, form a housing to receive the reduced end 8, of the shackle 6.

These locking tongues 11 and 12, are stamped from the body of the section 13, the reduced ends thereof extending toward the rear edge 19 of the section 13 or in a direction opposite to the direction of travel of the shackle 6, if the same is being removed from its locked position.

In the seal, when formed, section 13 overlies the central section 5, the section 15, is now folded over to substantially house the section 13, the narrow section 16 being now folded downwardly to embrace the edges of the section 13 and central section 5, for securing the sections of the body together.

The locking tongues 12 and 13, are now lying within the confines of the depressions 9 and 10.

From the foregoing it will be seen that if the seal is to be locked, the shackle 6, or the pointed end 8 thereof, is forced between the central section 5, and lateral section 13, with the result that the locking tongues 11 and 12, will position themselves within certain

openings of the shackle, whereupon the locking tongues 11 and 12 again assume a position within the depressions 9 and 10.

It is obvious, that if a tool or instrument 5 were inserted within the end of the body, to bend the tongues 11 and 12 upwardly, out of their locked position, the tool would ride over the inclined surface of the tongues, and would not engage under the tongues, to permit 10 the same to be pried upwardly, due to the fact that the extreme ends of the tongues are guarded by their positions within the depressions 9 and 10.

Having thus described the invention, what 15 is claimed is:—

In a seal, a central section having spaced 20 depressed portions, a shackle formed integral with the central portion, said shackle being of a width less than the width of the central portion, a lateral section formed integral with the central portion, said lateral section being of a length shorter than the length of the central section to provide a

shoulder, said lateral section having tongues formed therein, said lateral section adapted to be folded over the central section so that the tongues thereof will lie in a position over the depressed portions, a lateral section having a relatively narrow section formed integral therewith, and forming a part of the central section, the last mentioned lateral section adapted to be folded over the first mentioned lateral section, said relatively narrow section adapted to engage the underside of the central section for locking the sections together, and said shackle having openings coöperating with the tongues for securing the shackle to the central section. 25 30 35

In testimony that I claim the foregoing as my own, I have hereto affixed my signature 40 in the presence of two witnesses.

HENRY C. DES COMBES.
